UNITED STATES PATENT OFFICE

FRIEDRICH SAUTER, OF WEINGARTEN, GERMANY

LETTER BOX

Application filed April 4, 1931. Serial No. 527,731.

This invention relates to a letter box of any kind and has for its object to close the slot of the letter box from the inner side by means of a resiliently mounted cylinder of suitable material, rotatably only in one direction in such a manner that, during the insertion of a letter into the box, the cylinder is pressed away from the slot and rotated by the letter inserted, in the direction of the insertion. Consequently the removal of letters by unauthorized persons through the insertion slot is rendered impossible.

If the letter should remain suspended between the inner end of the slot and the cylinder, it is sufficient to slightly depress the cylinder by hand, thereby releasing the letter which must then positively drop into the box. The cylinder is made rotatable in one direction and locked in the other direction, in order to render it absolutely impossible to remove letters through the slot, using accessory means, such as wire hooks, sticks coated with adhesive material or the like. The suitably locked cylinder covering a certain portion of the slot has been proved to be a reliable preventative in all instances.

A house letter box is illustrated in side elevation by way of example in the only figure of the accompanying drawing, with one side wall removed.

The letter box is designated by 2, its door by 3, its rear wall by 4, the top plate by 5 and a slot in the top wall by 6. On the front wall 7, two resilient supporting bars 8 are fixed. In the bearings 9 fixed each to one supporting bar, journals 11 of a cylinder 10 are rotatably mounted. One of the two resilient supporting bars 8, that shown in the drawing, carries a resilient locking pawl 13 in the form of a steel strip, rigidly fixed by means of rivets or the like, which pawl engages in a ratchet wheel 14, rigidly connected to and rotated with the cylinder 10. Thus the cylinder 10 can only rotate in the direction indicated by the arrow, namely in the insertion direction.

Finally a holder 16 for newspapers or large printed matter, which, owing to their size 50 cannot be inserted in the box, is fixed on the

lower surface of the bottom plate 15 of the box.

The above described cylinder can also be employed for protecting postal letter boxes, in which the insertion slot is usually arranged in the side walls and which are also exposed to theft. 55

I claim:—

A letter box, comprising in combination with the box having an insertion slot, a cylinder in said box adapted to engage in said slot, two resilient supporting bars mounted on the inner side of one of the walls of said box rotatably carrying said cylinder adapted to press said cylinder into and close said slot, a ratchet wheel on one end of said cylinder, and a resilient steel strip rigidly fixed at one end on one of said bars engaging with its free end said ratchet wheel, adapted to cooperate with said ratchet wheel to allow said cylinder to turn in the direction necessary for inserting a letter in said slot and to lock said cylinder against rotation in the opposite direction. 70

In testimony whereof I affix my signature.

FRIEDRICH SAUTER. 75
